UNITED STATES PATENT OFFICE.

OTTO A. LEHMAN, OF HOBOKEN, NEW JERSEY.

DESIGN FOR A PORTE-MONNAIE OR CARD-CASE.

SPECIFICATION forming part of Design No. 30,170, dated February 14, 1899.

Application filed November 18, 1898. Serial No. 696,645. Term of patent 7 years.

To all whom it may concern:

Be it known I, OTTO A. LEHMAN, a citizen of the United States, and a resident of Hoboken, in the county of Hudson and State 5 of New Jersey, have invented and produced a new and original Design for Porte-Monnaies or Card-Cases, of which the following is a specification, reference being had to the accompanying drawings, forming a part thereof.

10 The leading feature of my design consists in a porte-monnaie or card-case presenting in front elevation an overlying flap partially concealing the front face of the porte-monnaie or card-case and when viewed in end elevation presenting a U-shaped outline, an intermediate partition terminating in the flap overlying one branch of the U-shaped outline and an inverted-V-shaped outline interposed between the aforesaid intermediate 15 partition and the other branch of the U-shaped outline.

20 In the accompanying drawings, Figure 1 is a view of the porte-monnaie or card-case in

front elevation, and Fig. 2 is a view of the same in end elevation.

25 A represents the front branch of the U-shaped outline.

A' represents the other branch of the U-shaped outline.

B represents the overlying flap.

30 C represents the intermediate partition, and D represents the inverted-V-shaped outline between the intermediate partition C and the branch A' of the U-shaped outline.

35 What I claim is—

The design for a porte-monnaie or card-case substantially as herein shown and described.

40 In testimony that I claim the foregoing as my invention I have signed my name, in presence of two witnesses, this 10th day of November, 1898.

OTTO A. LEHMAN.

Witnesses:

BRUNO BERGMANN,
CHAS. H. MICHAELSEN.
